F. M. McMASTER

HAIR MARCELLING DEVICE

Filed Jan. 16, 1926

Patented July 12, 1927.

1,635,683

UNITED STATES PATENT OFFICE.

FLOSSIE M. McMASTER, OF SAN JOSE, CALIFORNIA.

HAIR-MARCELING DEVICE.

Application filed January 16, 1926. Serial No. 81,679.

This invention relates particularly to a hand tool for use in marceling the hair.

It is one object of the invention to provide a device of the character indicated that 5 will impart the desired wave to a large quantity of the hair at one application.

It is another object of the invention to provide a device of the character indicated that will effectually impart the desired double wave to the hair required in this form 10 of hair dressing.

It is also an object of the invention to provide a device of the character indicated that will be simple in construction, economical to 15 manufacture, and highly efficient in its practical application.

In the drawing:—

Figure 1 is a plan view of a device embodying my invention.

20 Figure 2 is a side elevation of the same.

Figure 3 is a sectional view on line 3—3 of Figure 1.

Figure 4 is a transverse sectional view 25 through another embodiment of my invention.

Referring more particularly to the drawing, I show at 1 a handle carrying an end portion 2 bent into a wave formation as indicated at 3, the several portions of these 30 waves lying in a single plane and designed to lie parallel with the body of hair to be treated.

The main body portion of the device as 35 herein disclosed is made of sheet metal having the following characteristics in transverse cross-section. The central portion of the sheet metal plate engages the under side of the end portion 2, to which it is secured in any suitable manner as by rivets 5, the 40 portions of the plate 4 on either side of the portion 2 being bent upwardly a distance as at 6, thence outwardly a distance as at 7 and again downwardly a distance as at 8 into the general form of the letter M.

45 At 9 is shown an upstanding element mounted on handle 1 a distance from the sheet metal portion 4, and on this element 9 is pivotally mounted a second handle part 10. The handle part 10 as herein disclosed 50 comprises two flat bars riveted together as at 11 and passing on either side of the element 9 as shown, the two bars 12—13 forming handle 10 separating a distance forwardly of the element 9 as shown at 14—15 respectively. These two parts are then bent 55 forwardly again into parallel relation to

each other as shown at 16—17 and twisted as at 18—19 so that their forward portions lie in a plane parallel with the plane of sheet metal portion 4, as indicated at 20—21. 60 These parts 20—21 are of such a size and conformation as to readily pass into and out of the curved channels or recesses 22—23 formed in the sheet metal body portion 4 as hereinbefore described. 65

The parts 10 to 21 inclusively are so formed and constructed and arranged relative to the handle 1 that when the handles are brought together the parts 20—21 fit snugly into the recesses 22—23 and consequently apply the 70 desired pressure to the hair placed therein. The side walls 6 and 8 of these recesses preferably converge slightly toward the top to permit the proper manipulation of the hair therein. 75

In its practical application the device is, of course, heated as desired and then the laterally undulating end portions 20—21 are inserted under a quantity of hair, the handle 10 being held in the position shown in 80 dotted lines at 24 for this purpose. When the handles are brought together as shown in solid lines the hair supported on the parts 20—21 is pressed up and into the recesses 22—23 and tightly held between the flat 85 parts 20—21 and 7—7.

It may be readily seen from the foregoing that in the one operation the hair is given the desired wave in the plane of the body portion 4 and also given the desired wavy or 90 formation in planes at right angles thereto.

While this is, perhaps, the simplest form of the invention, it may also be made with a hollow handle portion as indicated at 25 in Figure 4 to accommodate wires as 26 for 95 heating the coil 27. The electrically heated coil 27 is arranged on the outer surface of the sheet metal portion 4 and enclosed in a covering 28.

It is to be understood, of course, that while 100 I have herein shown and described but two specific embodiments of my invention, changes in form, construction and method of operation may be made within the scope of the appended claims. 105

I claim:—

1. A device of the character described, comprising a handle, a sheet metal body having laterally undulating undulations formed therein and having its central portion mounted on said handle, the said body portion being bent upwardly a distance on each side 110

of said handle, thence outwardly a distance, and thence downwardly a distance to form flat bottomed grooves, an upstanding bracket mounted on the handle a distance from the said body portion, and a second handle part 5 pivotally mounted on said bracket and provided with spaced flat prongs adapted to engage the flat bottomed grooves in said body portion.

10 2. A device of the character described, comprising a handle, a sheet metal body having laterally undulating undulations formed therein and having its central portion mounted on said handle, the said body portion

being bent upwardly a distance on each side 15 of said handle, thence outwardly a distance, and thence downwardly a distance to form flat bottomed grooves, an upstanding bracket mounted on said handle a distance from the said body portion, and a second handle pivotally mounted on said bracket and comprising 20 a pair of flat bars secured together throughout the major portion of their lengths but separated and twisted at one end to form prongs adapted to engage the flat bottomed grooves in said body portion. 25
